UNITED STATES PATENT OFFICE.

RUDOLPH CONRADER, OF ERIE, PENNSYLVANIA.

LUBRICATOR.

1,316,832.

Specification of Letters Patent. Patented Sept. 23, 1919.

Application filed December 7, 1917. Serial No. 205,924.

To all whom it may concern:

Be it known that I, RUDOLPH CONRADER, a citizen of the United States, residing at Erie, in the county of Erie and State of Pennsylvania, have invented new and useful Improvements in Lubricators, of which the following is a specification.

This invention relates to lubricators and consists in certain improvements in the construction thereof as will be hereinafter fully described and pointed out in the claims.

The lubricator is designed for use with fluid actuated or actuating devices and is of particular advantage when used in connection with pneumatic hammers.

The invention is illustrated in the accompanying drawings wherein the invention is adapted to a pneumatic hammer as follows:

20 Figure 1 shows a front elevation of the lubricator.

Fig. 2 a section on the line 2—2 in Fig. 1.

Fig. 3 a plan view of the lubricator.

25 Fig. 4 a plan view of the lubricator with the handle for the plunger screw removed.

Fig. 5 a side elevation of a hammer with the lubricator in place.

1 marks the hammer cylinder, 2 the handle, 3 the lever for actuating the hammer 30 controlling valve, 4 a flexible connection for supplying air to the hammer, and 5 the usual screw connection in the hammer handle for the flexible connection. These parts are of ordinary and common construction.

35 The lubricator has the connecting fitting 6 with a screw-threaded end 7 adapted to enter the screw-threaded connection 5. A screw-threaded connection 8 similar to the 40 connection 5 is provided at the opposite end of the fitting 6 and is adapted to receive the union 8^a on the flexible connection 4. The lubricator in this way is simply interposed between the flexible connection 4 45 and the handle and requires no alteration in these parts.

A screw-threaded receptacle head 9 is formed on the fitting 6 and a passage 10 leads from the inner face of this head along 50 the walls of the fitting to the end of the fitting so as to deliver oil into position to be entrained by the air passing through the fitting. A receptacle 11 is screwed into the head 9. A plunger 12 operates in the 55 receptacle 11 and forces oil from the receptacle through the passage 10. The

plunger 12 is mounted on a screw 13. The screw 13 has an extension 14 extending through the end of the receptacle. A handle 15 is secured to the extension 14 by means of 60 a pin 16. It will be readily seen that by turning the handle 15, the screw 13 is rotated and the plunger 12 advanced so as to force oil from the receptacle.

In order to lock the screw in adjustment 65 and to nicely determine the amount the screw is actuated so as to control the amount of oil or grease fed I provide a yielding detent catch for the handle. Sockets 17 are formed in the handle. Pawls 18 are arranged in these sockets, the pawls having the stems 19 extending through perforations 21 in the rear walls of the sockets. Springs 20 are arranged in the sockets around the stem 19 and exert pressure against the pawls 75 18. Detents 22 are arranged in the face of the end of the receptacle in the path of the pawls 18 as they are rotated. I prefer to provide a series of pawls and a series of detents having a different number of pawls 80 than detents. As shown there are four pawls and five detents. As a result one pawl will be in register with a detent at the same time but it will be observed that but a very slight movement is required to bring some 85 one of the pawls into register with some one of the detents. The effect of this construction is to make a very fine graduation of the adjusting mechanism with but a few detents and pawls.

90 The stem has a closure disk 23 formed upon it which operates on a seat 23^a in the end of the receptacle. This disk is initially held to its seat by the pressure of the springs 20 operating against the pawls, the pressure 95 tending to force the handle away from the end of the receptacle and in consequence exerting pressure on the disk through the stem extension.

The plunger is preferably provided with 100 a cup 24. This is supported in place by the plunger disk 25 and is held in place by the nut 27 which is screwed onto the screw-threaded hub 26 on the plunger.

The plunger offers sufficient frictional resistance to prevent its turning when the screw is operating.

105 When the hammer is operating the air pressure is delivered to the receptacle through the passage 10 and the tendency 110 would be to force the oil or grease in the receptacle past the plunger into the space

below the plunger. To obviate this tendency I provide a neutralizing passage so that the pressure on the plunger is balanced. This is conveniently accomplished by extending the stem 13 through an opening 28 in the fitting 6. A passage 29 is arranged in the stem and communicates through a lateral passage 30 with the part of the receptacle back of the plunger.

With this construction the grease or oil can be forced forward and the amount fed can be very accurately controlled. When it is desired to fill the receptacle it is only necessary to unscrew the receptacle from the head 9 and the cup can be filled with grease or oil the plunger having been retracted by operating the screw.

By utilizing a screw locked against movement in an axial direction for actuating the plunger, the lubricator can be made to occupy very little space. While this is of advantage in many relations it is of particular advantage in a hammer which is being constantly manipulated.

What I claim as new is:—

1. In a lubricator, the combination of a cylinder; a fluid connection leading to the cylinder; and a lubricator delivering oil in position to be entrained by the fluid supplied by the connection, comprising an oil receptacle; means for exerting pressure on the oil in the receptacle for feeding oil from the receptacle; and means for delivering fluid from the fluid connection to the receptacle to neutralize the back pressure on the oil in the receptacle.

2. In a lubricator, the combination of a cylinder; a fluid connection leading to the cylinder; and a lubricator delivering oil in position to be entrained by the fluid supplied by the connection comprising an oil receptacle; a plunger in the receptacle; means for actuating the plunger to deliver oil; and means for neutralizing by fluid pressure the back pressure against the discharge of oil.

3. In a lubricator, the combination of a cylinder; a fluid connection leading to the cylinder; and a lubricator delivering oil into position to be entrained by the fluid supplied by the connection, comprising an oil receptacle; a plunger in the receptacle, said receptacle having an oil passage leading from one side of the plunger to a position to deliver oil to the fluid passing to the cylinder; a passage leading to the other side of the plunger for neutralizing the pressure on the plunger; and means for actuating the plunger.

4. In a lubricator, the combination of a cylinder; a fluid connection leading to the cylinder; and a lubricator delivering oil in position to be entrained by the fluid supplied by the connection, comprising an oil receptacle; a plunger in the receptacle;

means for actuating the plunger to deliver oil comprising a yielding detent catch for locking the plunger in adjustment; and means for neutralizing by fluid pressure the back pressure against the discharge of oil. 70

5. In a lubricator, the combination of a cylinder; a fluid connection leading to the cylinder; and a lubricator delivering oil into position to be entrained by the fluid supplied by the connection comprising an oil 75 receptacle; a plunger in the receptacle for forcing oil from the receptacle into position to be entrained by the fluid delivered to the cylinder; means for actuating the plunger comprising a screw locked against axial 80 movement; a stem for effecting a relative movement of the screw and plunger for adjusting the plunger; and a yielding detent catch for locking the stem in adjustment.

6. In a lubricator, the combination of a 85 cylinder; a fluid connection leading to the cylinder; and a lubricator delivering oil into position to be entrained by the fluid supplied by the connection comprising an oil receptacle, said receptacle having a feeding passage 90 for the delivery of oil into the fluid delivered to the cylinder; a plunger in the receptacle; a screw on which the plunger is mounted; and a passage through the screw for delivering fluid to the side of the plunger opposite the feeding passage. 95

7. In a lubricator, the combination of a cylinder; a fluid connection leading to the cylinder; and a lubricator delivering oil into position to be entrained by the fluid supplied 10 by the connection comprising an oil receptacle; devices for delivering oil from the receptacle to the fluid passing to the cylinder, comprising a stem which is rotated in the operation of the devices; a screw operated 10 by the stem; and a yielding detent for locking the screw in adjustment.

8. In a lubricator, the combination of an oil receptacle; devices for delivering oil from the receptacle comprising a screw; a stem 11 operating in connection with the screw to adjust the devices; and a yielding detent device for locking the stem in adjustment comprising a series of detents and a series of pawls, one series rotating with the stem and 11 the number of detents differing with the number of pawls.

9. In a lubricator for pneumatic hammers, the combination of a hammer cylinder; a handle therefor; a flexible air connection 1 leading to the handle; and a lubricator secured to the handle and interposed between the handle and the flexible connection, said lubricator comprising means for delivering oil into position to be entrained by the air 1 going to the hammer.

10. In a lubricator for pneumatic hammers, the combination of an air fitting; a receptacle on the fitting; a plunger in the receptacle; a screw on which the plunger is 1

mounted; a handle for operating the screw; and a yielding detent catch on the handle for locking the screw in adjustment.

11. In a lubricator, the combination of an oil receptacle; a plunger in the receptacle; a screw on which the plunger is mounted, said screw having a longitudinal passage and a

lateral passage leading to the receptacle back of the plunger; and a feeding passage leading from the receptacle.

10 In testimony whereof I have hereunto set my hand.

RUDOLPH CONRADER.
